UNITED STATES PATENT OFFICE

96,355

DESIGN FOR A SANITARY FORK

Michael Tecca, Toronto, Ohio

Application May 21, 1935, Serial No. 56,940

Term of patent 14 years

To all whom it may concern:

Be it known that I, Michael Tecca, a citizen of the United States, residing at Toronto, in the county of Jefferson and State of Ohio, have invented a new, original, and ornamental Design for a Sanitary Fork, of which the following is a specification, reference being had to the accompanying drawing, forming part thereof.

I claim:

The ornamental design for a sanitary fork as shown.

MICHAEL TECCA.
